UNITED STATES PATENT OFFICE.

LESTER B. CHISHOLM, OF STONEHAM, MASSACHUSETTS.

COVERED ELASTIC THREAD OR THE LIKE.

Application filed January 3, 1927. Serial No. 158,622.

The invention relates to an improvement in covered elastic threads or the like useful in the making of elastic fabrics, and the object of the invention is to overcome certain defects inherent in these threads as now commonly employed.

Where an elastic thread is employed in the making of an elastic fabric difficulty arises in case one of the elastic threads is broken, 10 as for example when the fabric is being machine-sewed the needle may sever some one of the elastic threads. The effect is when one of the elastic threads is broken for the severed ends of the thread to draw or run 15 into the fabric which effect is aggravated because the thread usually lies within the fabric under some tension. After the ends of the broken thread have run or contracted into the fabric the thread will lie substantially inert, no longer functioning as an elastic. Not only this, but the inelastic thread covering with which the elastic thread or core 20 is provided, no longer being supported along the point of the cut will tend to unwind and become loose, giving the fabric an unsightly appearance at the point where the break or cut has occurred. The object of the invention, as said before, is to overcome this difficulty, and the way in which it is overcome 25 can best be seen and understood in the light of the drawings in which—

Figure 1 is a short section or piece of elastic core thread.

Fig. 2 shows this same thread twisted.

Fig. 3 shows the core thread provided with its inelastic thread covering in accordance with the principles of the invention as will hereinafter be explained, and

Fig. 4 is a section of the elastic core thread 40 and inelastic thread covering, more or less diagrammatic, for illustrating the principles inherent in the invention.

Referring to the drawings:—

1 represents the elastic core thread. This 45 thread is of a type commonly employed in elastic fabrics and is usually square in cross section.

This thread is made to have a slip-resisting 50 surfacing 2. For obtaining such surfacing the thread has applied to it some substance that will make the surface of the thread of a slip-resisting character. This may be, and preferably is, accomplished by running the thread through a bath of rubber cement, preferably leaving the cement 55 unvulcanized on the surface of the thread,

thereby making the surface more or less tacky.

After the surfacing of the thread it is twisted, this being effected while the thread 60 is stretched or taut and the twist is preferably continued to a point where, when the thread is allowed to relax, its outer surface will present the appearance of a multiplicity of spiral coils. In other words, the elastic core is rather hard twisted, although the 65 twist is not carried so far that it will in any way interfere with the functioning of the core as an elastic medium, but will rather tend to increase it. 70

The twisted elastic core thread held taut is then provided with an inelastic thread covering 3. This covering is wound around the core thread with coils running spirally 75 in a direction reverse to the direction in which the core thread is twisted. After the winding of the thread covering, which may be accomplished by any suitable means, the covered core thread is allowed to relax and assume its normal shape when the coils of 80 the covering will be brought together contacting with one another which defines the normal length of the structure, the core thread then being maintained under some tension within the covering. 85

When a covered thread is thus made, if the core thread be cut or broken at any point the tendency will be for it to untwist. The direction of its untwisting will be in the direction that the coils of the thread 90 covering are wound, and accordingly the core thread, tending to untwist, will frictionally grip the coils of the thread covering and will thereby tend to further wind the covering at the point where the core thread 95 is cut or tends to untwist. This has the resulting effect of tightening the thread covering onto the core thread, thereby preventing the core thread from drawing back into the fabric and at the same time winding 100 up the thread covering at the point of rupture so that in the fabric the thread covering will present no unsightly appearance as any looseness in the thread covering at the point of rupture is taken up. 105

Instead of using a single twisted core thread for forming the elastic core, more than one thread, as for example two or three elastic threads twisted together, may be employed and precisely the same principle prevail with even increased effect. 110

Having thus fully described my invention,

I claim and desire to secure by Letters Patent of the United States:—

1. An article of manufacture comprising a twisted elastic core having a slip-resisting surfacing and a non-elastic thread covering wound spirally around said twisted core in a direction reverse to the direction of twist in said core.

2. An article of manufacture comprising a twisted elastic core and an inelastic thread covering with coils wound spirally around said core in a direction reverse to the direction that said core is twisted whereby said core will tend to untwist in the same direction that said thread covering is wound and by its frictional engagement with the coils of said covering will tend to further wind the covering.

3. An article of manufacture comprising a twisted elastic core having a slip-resisting surfacing and an inelastic thread covering

with coils wound spirally around said core in a direction reverse to the direction that said core is twisted whereby said core will tend to untwist in the same direction that said thread covering is wound and by its frictional engagement with the coils of said covering will tend to further wind the covering.

4. An article of manufacture comprising a twisted elastic core, a slip-resisting surfacing material or cement applied to the surface of said core, and an inelastic thread covering with coils wound spirally around said core in a direction reverse to the direction that said core is twisted whereby said core will tend to untwist in the same direction that said thread covering is wound and by its frictional engagement with the coils of said covering will tend to further wind the covering.

LESTER B. CHISHOLM.
